TOE PLEDGET

Burton D. Morgan, Loudonville, N. Y.

Application January 7, 1953, Serial No. 330,119

7 Claims. (Cl. 128—153)

1

My invention relates to a toe pledget or pad which is a soft article adapted to be placed between the toes of a person for preventing friction and to guard against infection or to provide medication for treatment of such infections as that known as athlete's foot. It is an object of the invention to provide a pledget that can be manufactured in cheap and simple manner, and which shall be particularly adapted for the use indicated, though a pad of the general type herein disclosed is not necessarily limited to the use indicated.

Another object of the invention is to provide a toe pad that is useful for prevention of infection or disease of the feet, and which will absorb perspiration and other moisture and so tend to keep the feet in sanitary odor-free condition.

Another object is to provide a pledget that fits easily and naturally between the toes and is less likely to become displaced than such toe pads as are now in use.

Referring now to the annexed drawings, which are made a part of this application and in which similar reference characters indicate similar parts;

Fig. 1 is an elevation of a blank, which is a strip or length of material in an intermediate stage of manufacture, from which blank several pledgets may be made by further operations,

Fig. 2, a section on line 2—2 of Fig. 1,

Fig. 3, a view similar to Fig. 1, illustrating a method of stamping or cutting out pledgets from a blank like that of Fig. 1, with little or no waste,

Fig. 4, a section on line 4—4 of Fig. 3,

Fig. 5, a view illustrating the formation of pledgets of different shape from those of Fig. 3, and without any waste, and

Fig. 6 illustrates the formation of still another form of pledget, involving some waste, but providing a pledget of especially pleasing shape and appearance.

In the drawings, reference character 10 indicates a pair of rovings or slivers of small diameter that are fed in parallelism to each other while a ribbon of drawn cotton 11 is wound about them in spiral form. Preferably the slivers are slightly twisted, while the covering cotton may have the form of a ribbon without any twist, and all of these strand-like or ribbon-like members preferably consist of cotton or cellulose, though it is to be understood that other natural or artificial fibers can be used if desired, the qualities most necessary being softness and absorptiveness.

The slivers 10, 10 will preferably be round in

2

cross section, as indicated in Fig. 2, but may become flattened during or after manufacture without material loss of function, and may even be flattened, more or less, previously to the application of the ribbon 11 without substantial detriment to their usefulness. At the first step of manufacture the slivers will be fed in the relation shown in Fig. 1, or may be held in such position while the ribbon is laid about them in a spiral, but it is also possible to apply loose flock of cotton or other fiber to a rotating core including a pair of spaced cords in a cloud of sufficient density to cause formation of a strip like that of Figs. 1 and 2, and other methods of forming the strip will suggest themselves to those skilled in the textile art. By the term "sliver" there is intended a linear strand-like body usually having a slight twist, whereas a roving has no twist or very little twist and a wadding is of ribbon-like form but generally without twist. All such bodies consist of fibers, but it will be understood that the bodies 10, 10 may be in the form of very soft cords or cables without losing their usefulness for the purpose indicated, and the ribbon 11 may have considerable cohesiveness and still perform the indicated functions.

After the first step the strip may have the form of Figs. 1 and 2, and thereafter the pledgets may be completed in various ways and in various shapes. In a preferred mode of operation pledgets 12 will be stamped from the strip as illustrated in Fig. 3, where the outline is indicated by line 13 and the sides are compressed as indicated at 14 to form a central lozenge-shaped compressed area 14 to accommodate the sides of the adjacent toes.

As indicated in Fig. 5, pledgets 16 may be stamped out from a strip in the shape there shown, and they may have a compressed area of any desired shape within the confines of the outline of the pledgets.

In another form that the invention may take, pledgets 17 may be stamped out from a strip such as that of Figs. 1 and 2, the small portions at 18 being wasted in the use of such method of stamping, as in Fig. 6.

In each form of the pledget there is a main or body portion shaped to fit between the toes and a rearward extension 19 shaped to extend back of the region of the root of a toe and to lie to some degree upon the upper surface of the foot adjacent the roots of the toes. The extension aids in positioning the pledget and helps to prevent excessive downward movement of the pledget toward the space beneath the foot.

It will be seen that the pledges made according to this invention are somewhat thickened at the upper and lower margins, and these thickened parts will lie respectively above and below the thickest portions of the toe, and so tend to hold themselves in place while in use. Besides being capable of rapid manufacture, the materials are cheap and, therefore, the production is rapid and inexpensive.

It will be obvious to those skilled in the art that many variations can be made in the invention disclosed herein, all without departing from the spirit of the invention; and therefore I do not limit myself to what is shown in the drawings and described in the specification, but only 10 as indicated in the appended claims.

Having thus fully disclosed my invention, what I claim is:

1. A toe pledge comprising a body of soft fibers shaped to lie between the toes, parallel 20 lengths of soft cord embedded in said body and adapted to lie respectively above and below the toes, and a rearward extension shaped to lie upon the foot rearwardly of the roots of the toes.

2. A toe pledge comprising spaced-apart soft 25 fibrous cords and a wrapping of wadding covering the cords and the intervening space.

3. A pledge as in claim 2, wherein the cords are spaced to lie respectively below and above the adjacent toes while said wrapping separates said toes from one another.

4. A device as in claim 3, said wadding being wrapped spirally about the cords.

5. A toe separating pledge, comprising parallel soft strand-like linear bodies, and a wrapping of ribbon-like wadding enclosing said bodies, said pledge having a main portion shaped to fit between the toes, and a rearward extension shaped to reach beyond the roots of the toes and to rest upon the foot.

6. A toe pledge comprising spaced-apart strand-like cellulosic bodies, and a strip of cellulosic material enclosing said bodies.

7. A device as in claim 6, said strip being wrapped spirally about said bodies.

BURTON D. MORGAN.
